UNITED STATES PATENT OFFICE.

FRANK F. LANDIS, OF WAYNESBOROUGH, PENNSYLVANIA.

GANG-PLOW.

SPECIFICATION forming part of Letters Patent No. 352,196, dated November 9, 1886.

Application filed June 16, 1884. Serial No. 135,013. (No model.)

To all whom it may concern:

Be it known that I, FRANK F. LANDIS, a citizen of the United States, residing at Waynesborough, in the county of Franklin and State of Pennsylvania, have invented certain new and useful Improvements in Gang-Plows, of which the following is a specification, reference being had therein to the accompanying drawings.

10 This invention relates to gang-plows, and has reference more particularly to the means employed for connecting the gang of plows to a traction-engine or other similar motor; and one of the principal objects of the invention is to connect the gang to the axle of the motor in such a manner that the plowing mechanism shall always be maintained at a height from the ground corresponding with the axle, while at the same time the body of the motor shall 15 20 be capable of vertically oscillating on the axle, and said oscillations of the motor are prevented from causing similar movements in the plowing mechanism.

Other objects and advantages of the invention will be hereinafter described, and the novel features thereof be specifically set forth in the claims.

Referring to the drawings, Figure 1 is a plan; Figs. 2 and 3, side elevations; Fig. 4, a 25 bottom plan of portions of a motor and gang-plow sufficient in extent to clearly illustrate my invention. Fig. 5 is an enlarged detail of the adjustable suspension-link and its adjuncts.

Like letters indicate like parts in all the figures.

35 With the axle A the motor B is connected in any suitable well-known manner, and the same choice and arrangement in regard to the manner of connection of the drivers C to the axle is left to the judgment and discretion of the builder.

The gang-plow frame comprises a straight draft-beam, D, and diagonal gang-beam E, and a transverse draft-beam, F, connecting the 40 45 straight and diagonal beams and arranged at the rear of and near the motor. The rear end of the straight and diagonal draft-beams are united in the casting E', adapted to receive said ends and to be secured thereto, and also

50 adapted to receive the spindle of a caster, E''. The straight draft-beam is extended toward

and terminates at a point directly beneath the projecting end of the axle, and is adapted to be connected to the axle by a suspension-link, G, which may be of any suitable construction, 55 which admits of its adjustment to the axle and to the draft-beam, and which is also preferably adapted to support the said beam at a distance below the axle. A preferable form of said link is illustrated in Fig. 5, and is hereinafter 60 described, although I wish it understood that I do not limit my invention to any form of suspension-link, as the beams D and E may be curved upwardly and mounted directly on the axle; but the link may even be dispensed with 65 and a wheel may be substituted, as shown in a companion application, to carry the forward ends of the beams a uniform distance from the ground. The gang-beams D and E may, however, be extended in a straight line to 70 such a distance that their front ends terminate at and below the axle A, (see Figs. 2, 4, and 5,) which is itself also extended outward from the drivers C, either in a single continuous piece (see dotted lines, Fig. 1) or with an extension 75 piece or bearing held by the brace C' at such a distance as to terminate above the ends of the said gang-beams, in which case suspension-links G are employed in order to support the gang-beams at a desired distance below the 80 axle. When the axle is continuously extended beyond the traction-wheel C, the braces C' extend from the tire to a collar or flange, C'', mounted upon an extension of the axle, so that the said extension is strengthened against deflection from a right line.

By the construction thus far described I have provided means whereby the frame of the gang-plow is supported at a desired distance from the ground, and such a distance is maintained without regard to any oscillations of the body of the motor B, because as the traction-wheels follow the undulations of the ground the gang-beams, with or without the suspension-links, as a matter of course must 95 follow the axle and wheels.

Now, it remains to provide draft devices which are adapted to work in connection with the devices already described for maintaining the plow-frame at a uniform height.

To the transverse beam F is secured a series of draft-rods, F', which in this instance are

connected to a series of eyebolts, F², by a rod, F³, said eyebolt being passed horizontally through the draft-beam F. The opposite ends of the bars are gathered in a short bar, F⁴, from the front ends of which extend radius-bars F⁵, adapted by means of a turn-buckle or other suitable device to be adjustable lengthwise, which radius-bars are connected in any suitable manner to the motor. The short bar F⁴ (see Fig. 3) is connected to the lower ends of the bolts H, which bind the box I of the axle, the frame J, (shown in dotted lines,) and the cushioning-springs K and their upper and lower stirrups L together, so that the connecting-link from the transverse bar F to the motor B comprises the bars F⁴, the short bar F⁵, and the radius-bars F⁶, together with any suitable means for connecting the said radius-bars to the motor—as, for example, the bracket F⁶, secured to the boiler-frame for supporting the said boiler, to which bracket, by means of a bolt or bolts, F⁷, the radius-bars F⁶ are secured. Said radius-bars may be secured to any suitable part of the motor, and I do not limit my invention to the exact means of either connection just described. Now, it will be observed that the oscillations of the motor are absorbed by means of the pivotal connection of the radius-bars or draft-bars with the motor, the transverse draft-beam, and the short bar, and by the cushioning-springs K, and that the pivotal action of the parts upon each other between the points of attachment F² F³ of the radius and draft-bars, respectively, serves the purpose in view—mainly to permit a direct attachment of the gang-frame and the motor for draft purposes, which shall at the same time conform to the work satisfactorily in connection with the direct connection of said frame with the axle to secure uniformity of distance of said frame to the ground at all times.

A very important advantage is now readily apparent, in that the line of draft is central and extended completely across the gang-frame, and I deem it proper to state at this point of the description that the diagonal and straight beams of the gang-frame may be directly connected to the ends of the axle, and thus insure the same advantage of uniformity of distance from the ground, and in such a construction the links G would be dispensed with and an equivalent thereof would be provided, the eyebolts F² or their equivalents would be extended vertically through and to a sufficient distance above the upper surface of the transverse draft-beam F to permit of a desirable connection of the draft-bars therewith; but in view of the fact that the most desirable diameter of a traction-wheel is such as to bring the gang-frame at too high an elevation from the ground if directly connected therewith, I prefer the construction shown and more particularly described, and even the objection just mentioned may be overcome in a great measure by curving the front ends of the straight and diagonal beams of the gang-frame upwardly and connecting them directly

with the axle, instead of employing a suspension-link.

The preferred suspension-link G is shown clearly in Fig. 5, where the draft-bar D is provided with a casting, D', comprising a vertically-slotted lug perforated horizontally, as at D'', to receive the end of the link G, which is provided with a series of holes, g, whereby the gang-beam may be secured upon the link at different points of elevation. The upper portion of the link is bifurcated to form bolts G', which pass through a bearing-block, G'', mounted upon the extension of the axle, and are provided with nuts G³, resting upon the upper surface of the bearing-block, whereby further adjustment may be made by turning said nuts. A nut and washer, G⁴, or an ordinary pin, G⁵, may be employed to retain the beams or the bearing-blocks of the link against removal from ends or extensions of the axle. If desired, the connection of the front end of the bars F⁴ may be directly with the motor or directly with the axle—that is to say, the radius-bars may be dispensed with; but the principal object of the radius-bars being to retain the proper relation of the front end of the draft-bars to the motor, I prefer to retain said radius-bars. It is clear that the draft-bars F⁴ may be pivotally secured to the axle or directly to the motor in such manner as to prevent lateral spreading of said draft-bar, and that that portion of the axle within the braces and the driver C (see dotted lines, Fig. 1) may be dispensed with, said braces, collar, and the outwardly-projecting portions or extension of the axle alone serving as a bearing for the diagonal gang-draft beam, whether directly attached thereto or suspended therefrom by a link.

Having described my invention and its operation, what I claim is—

1. The combination of the traction-wheels and axle of a motor with a gang-plow frame having diagonal and straight draft-beams, said beams extended to points outside of said traction-wheels upon a vertical plane passing through the axle of said motor, with gang-frame draft-bars pivotally connected to the gang-frame and to the axle, substantially as described.

2. The combination of the traction-wheels and axle of a motor with a gang-plow frame having its diagonal and straight draft-beams extended to points outside of said traction-wheels, with gang-frame draft-bars pivotally connected to the forward side of the gang-frame and to the axle, and having adjustable radius bars F⁵, connected to the motor, substantially as described.

3. The combination of an extended axle, a traction-wheel mounted thereon, and a series of braces arranged on the outside of the wheel and terminating in a collar mounted on the axle, whereby the axle is adapted and strengthened for operation in connection with the extended diagonal gang-beam, substantially as specified.

4. The combination, with a gang-plow frame comprising extended straight and diagonal draft-beams, of a motor having an extended axle, and having braces arranged on the outside of one of the wheels of the motor, substantially as specified.
5. The combination of a motor having an extended axle and braces arranged on the outside of one of its traction-wheels, with a gang-plow frame having an extended straight draft-beam, an extended diagonal draft-beam, and a transverse draft-beam, and with pivotally connecting draft-bars and suspension-links connecting the axle with the gang-frame, substantially as specified.
6. The gang-plow frame comprising the draft-beam D, the diagonal gang-beam E, connected as at E', and provided with a caster, as E', and having a transverse draft-beam, F, in combination with a motor, B, having an extended axle, A, the connecting-links G, and the draft-rods F', pivotally connected with the axle and secured to the draft-beam by the eye-bolts F², and the rod F³, substantially as shown and described.
7. The combination, with the draft and gang beam of a gang-plow and the axle of a motor, of the suspension-links G, having the bolts G', and provided with holes for the attachment of the beam to the link, secured to the axle on 30 the outside of the driving-wheels of the motor, substantially as shown and described.
8. The combination of the axle A, the block G², and the link G, comprising the bolts G' and the nuts G', with the beam D or E, having the 35 casting D', secured to the beam and adapted for connection with the link, substantially as shown and described.
9. The combination of a motor with a gang-plow frame having diagonal and straight draft 40 beams, said beams extended to and connected with the ends of the axle of the motor, and draft-bars pivotally connecting the frame and the motor, substantially as specified.

In testimony whereof I affix my signature in 45 presence of two witnesses.

FRANK F. LANDIS.
